LIGHT SOCKET

Douglas T. Mitchell, Scarsdale, N. Y.

Application April 19, 1941, Serial No. 389,317

1 Claim. (Cl. 173—328)

My invention relates to light sockets provided with the bayonet type of groove, and has reference more particularly to the outer shell, and specifically to the means in such shell for mounting it on a suitable bracket.

The object of the invention is to provide a simple, inexpensive outer open type of shell, having shell mounting means which are adapted to draw the open edges of the shell together.

In the appended drawing forming part of this application,

Figure 1 is a top plan view of a single contact socket embodying my invention.

Figure 2 is an elevation of the socket.

Figure 3 is an elevation at right angles to that of Figure 2, partially in section on lines 3—3 of Figure 1.

Figure 4 is a bottom plan view of the socket.

Figure 5 is a top plan view of a double contact socket, and

Figure 6 is an elevation partially in section on line 6—6, Figure 5.

Referring to the drawing, particularly Figures 1 to 4, inclusive, 10 is an open shell formed out of a blank, having arms 11 and 12, at opposite ends, said arms being so arranged that there is a pair of spaced arms, 11, at one end to permit the arm 12 on the other end of the blank to pass therebetween when the blank is shaped into a sleeve. Arms 11 and 12 at the extremity thereof are looped, as shown at 13, to provide resilient clip like members which would yieldingly engage a flat bar, not shown, which generally is the support for such type of sockets.

Positioned within the shell 10 is a spring 14, the lower end of which engages lug 15, formed in the lower edge of the shell 10. The upper end of the spring carries a washer 16 of insulated material, the motion of which under the action of the spring is limited by prongs 17 formed in the sides of the shell 10.

Anchored to the central part of the washer 16 is a wire 18. The shell 10 above the washer 16 is provided with the bayonet slots 19 for engaging and retaining therein a bulb, not shown.

In Figures 5 and 6 the outer shell 10' has the arms 11' and 12', provided with the clips 13',

its bottom lugs 15' carry an insulated washer 20 through the opening 21, of which two wires 22 and 23 pass. The wire 22 is connected to an insulated washer 24, which is housed in an inner metallic shell 25, which metallic shell 25 is insulated from the outer shell 10', by an insulated sleeve 26.

The inner shell 25 carries a spring 27, the lower end of which rests on lugs 28, formed on the lower edge of the inner shell 25, while the upper end bears against the insulated washer 24, the motion of the washer 24 within the shell 25, being limited by prongs 29. The wire 23 is connected to the inner shell 25, said inner shell being provided with the customary bayonet slots 26.

Thus a two wire socket is formed, by the construction described, in which the outer shell, as far as its means for attaching to the support is concerned, is identical with that described for the single wire shell.

When either of those sockets are being mounted on a support, by engaging the loops or clips 13 with the support, the arms are forced to separate and thereby drawing the open edges of the shell together, in consequence gripping tightly the elements forming the socket located within the outer shell.

From the above description it will be seen that in my socket the outer shell may be said to have crossing arms provided at the extremity thereof, with means for mounting it on a suitable support, which means when engaging said support will cause the edges of the normally open shell to be drawn towards each other.

I claim:

In a light socket of the class described, an outer shell formed of a blank presenting crossing arms when the blank is shaped into a shell open longitudinally at the arms, said shell having stops at one end thereof formed by lugs projecting inwardly of the shell, said arms having yielding means at the extremities thereof for engaging a flat support so that the edges of the open shell are drawn towards each other when the arms engage a support.

DOUGLAS T. MITCHELL.
